UNITED STATES PATENT OFFICE.

JOHN L. DAY, OF MEMPHIS, TENNESSEE.

INDICATOR FOR VEHICLES.

1,054,511.

Specification of Letters Patent. Patented Feb. 25, 1913.

Application filed April 30, 1912. Serial No. 694,067.

To all whom it may concern:

Be it known that I, JOHN L. DAY, a citizen of the United States, residing at Memphis, in the county of Shelby and State of Tennessee, have invented certain new and useful Improvements in Indicators for Vehicles, of which the following is a specification.

My invention relates to improvements in indicators for vehicles, and is especially adapted for use in connection with automobiles and other vehicles as an illuminating means for license numbers, etc.

The object of the invention is the provision of an indicator for the purpose described which will be simple in construction, durable, and efficient in performing its functions.

The invention consists in certain novel combinations and arrangements of parts as will be hereinafter referred to.

In the accompanying drawings I have illustrated one complete example of the physical embodiment of my invention constructed according to the best mode I have so far devised for the practical application of the principles.

Figure 1 is a face view of an indicator embodying my invention. Fig. 2 is an end view of Fig. 1, looking from the right. Fig. 3 is a view similar to Fig. 1 with the number door or plate and screen omitted, and the hinged top lifted. Fig. 4 is a sectional view at line 4—4 Fig. 3. Fig. 5 is a section at 5—5 Fig. 2. Fig. 6 is a horizontal section on line 6—6 Fig. 1, with the number plate open.

In the preferred embodiment of my invention I employ a metallic casing comprising the bottom 1, rear side 2, and ends 3, 3, as usual. A lid or cover is hinged at 4 to the rear side 2 of the casing, and this lid comprises a hood 5 that is held elevated a distance above the shield 6 by means of 5 posts 7. A flue 8 is provided in the shield 6, and the location of the hood in its suspended position above the shield forms a space between the hood and shield, which together with the flue, provide for ventilation of the metallic casing. By means of the sliding bolt 9, one at each end of the casing, the lid may be secured in closed position.

The front door 10, which I shall hereafter term the number-plate, is hinged at 11 to 55 the bottom 1 of the casing, and by means of the slide bolts 12, may be locked in closed position. As clearly seen in Figs. 1, 6, and 4, the openings or perforations 13 in the number-plate are backed by a metallic screen 60 14 which is attached to the rear of the plate. This screen is provided to form a protection for the glass plates 15, 16, 17 (Fig. 3), which are held in between the frames 18 which form a part of the casing, and as 65 shown best in Fig. 4 the glass plates are directly back of the number plate.

Preferably the glass plates 15 and 17 are of ground glass, while the plate 16 is of red, so that when either the oil lamp 19 or 70 the electric lights 20 are lighted, the effect will be to show the numbers in white, and the round opening 21 as a red light or danger signal, while a clear glass 22 at one end of the casing shows a white light. 75

To increase the contrast between the color of the casing or number plate and the numbers in the plate, I may apply white paint or enamel to the screen 14 where it is exposed by the perforations, and the border 80 around the perforations may be colored.

While I have illustrated both electric and oil lamps, it will be understood of course that either of these lamps are to be used, or if desired a gas lamp of the acetylene type 85 might be used, in either event, the light is reflected by a reflector 23.

The reflector is preferably of nickeled brass, polished to a high degree, and preferably corrugated as shown, and it may be 90 removed for polishing.

It will be noted that the electric lamps 20 have individual reflectors 24, in addition to the reflector 23, and the lamps may receive current through the wires indicated at 95 25 from a suitable source of supply.

The casing of the indicator may be attached to a suitable part of the automobile frame by means of the strap 26 and clamp bolt 27, as will be understood. 100

In constructing the casing and doors, the joints are preferably riveted, to insure against the possibility of disconnection of joints should the heat become excessive in the casing, due to the lamps, as would likely 105 be the case with soldered joints.

Having thus fully described my invention, what I claim as new and desire to secure by Letters Patent is:—

5 In an indicator for vehicles, the combination with a casing having a light therein, of a frame at one side of the casing and differently colored glass plates in the frame, a hinged door in front of said frame having

indicating perforations, and a foraminous backing on said perforated door. 10

In testimony whereof I affix my signature in presence of two witnesses.

JOHN L. DAY.
